CLAIM

I claim the ornamental design for a light fixture, as shown and described.

DESCRIPTION

FIG. 1 is a top, front, left perspective view of an embodiment of the claimed design;

FIG. 2 is a bottom, front, left perspective view thereof;

FIG. 3 is a top plan view thereof;

FIG. 4 is a bottom plan view thereof;

FIG. 5 is a left side elevation view thereof;

FIG. 6 is a right side elevation view thereof;

FIG. 7 is a front elevation view thereof; and,

FIG. 8 is a rear elevation view thereof.

The ornamental design, which is claimed is shown in solid lines in the drawings. The broken lines in the drawings are for illustrative purposes only and form no part of the claimed design. Specifically, the dash-dot broken lines in the drawings are for the purpose of illustrating portions of the light fixture that form no part of the claimed design. The dash-dot broken lines in the drawings correspond to physical boundaries adjoining a bottom surface of the claimed design. The dash-dot broken lines, however, form no part of the claimed design.
